UNITED STATES PATENT OFFICE.

GEORGE DURYEE, OF NEW YORK, N. Y.

HYDROCARBON-FURNACE.

SPECIFICATION forming part of Letters Patent No. 253,270, dated February 7, 1882.

Application filed August 18, 1880. Renewed November 29, 1881. (No model.)

To all whom it may concern:

Be it known that I, GEORGE DURYEE, M. D., of the city of New York, in the county and State of New York, have invented new and 5 useful Improvements in Steam-Generators and Hydrocarbon-Furnaces, of which the following is a specification.

My invention relates to a combination of a steam-boiler and an apparatus for generating 10 and introducing therein a hydrocarbon blow-pipe flame, whereby steam of a high pressure may be economically produced. The boiler is preferably cylindrical, with a longitudinal flue, and it may be horizontal or vertical. The apparatus for generating the blow-pipe flame consists 15 essentially of an upright furnace, into the lower end of which is introduced a compound air and oil jet, which, being ignited, passes up through the furnace, and immediately opposite 20 the flue in the boiler is crossed and deflected by a blow-pipe jet, the two jets uniting and passing directly through the flue, thereby heating the boiler in the most favorable manner.

In order that my invention may be fully understood, I will proceed to describe it with reference 25 to the accompanying drawing, which represents a longitudinal section of a steam-generator embodying my improvements.

A is the boiler, shown in a horizontal position, and having a single flue, B, extending from end to end. There may, however, be any 30 number of flues.

C is an upright furnace placed immediately opposite one end of the boiler. Leading from 35 this furnace near its upper end is a flue, D, which projects within the flue of the boiler. Opposite this flue, and in line with it on the other side of the furnace, is a compound nozzle.

zle or blow-pipe, consisting of air-blast pipe E and interior oil-duct, F, the former leading 40 from a suitable blower and the latter from an oil-reservoir.

Near or at the bottom of the furnace C is a similar pipe, H I, having a much larger proportion of oil. This blast-pipe supplies the 45 furnace C with a large flame, which, ascending to the top of the furnace, is forcibly blown into the boiler-flue B by means of the more powerful blast issuing from the blow-pipe E F. The flame is designed to pass nearly or 50 quite the whole length of the boiler, and the air and oil supplies are so proportioned as to make a complete combustion of all the fuel.

The flue D may be dispensed with and the fuel-furnace C built in juxtaposition to the 55 boiler.

I disclaim invention in any of the elements of the apparatus, *per se*, my invention consisting in the particular combination of parts for the accomplishment of the purposes designated.

Having thus described my invention, the following is what I claim as new and desire to secure by Letters Patent:

A steam-generating apparatus consisting of 65 a boiler, A, having a flue, B, combined with an upright fuel-furnace, C, in front, and a compound blow-pipe delivering a blast of combined air and fluid fuel across the flame in the fuel-furnace in line with the boiler-flue, as described.

GEORGE DURYEE, M. D.
